(57) **CLAIM**

The ornamental design for a hook with receiving channels, as shown and described.

DESCRIPTION

FIG. 1 is a perspective view of a hook with receiving channels showing their new design;

FIG. 2 is an elevational view of a first face thereof;

FIG. 3 is the elevational view of the face opposite of FIG. 2;

FIG. 4 is a first side view thereof with the openings to the

channels;

FIG. 5 is a second side view thereof with the opening to the hook;

FIG. 6 is a top view thereof; and,

FIG. 7 is a bottom view thereof.

The nature and intended use of the article in which the design is embodied is a hook with receiving channels.
